ATT'Y

UNITED STATES PATENT OFFICE

ANDREW HAUGE, OF MICHIGAN CITY, INDIANA, ASSIGNOR TO SULLIVAN MACHINERY COMPANY, A CORPORATION OF MASSACHUSETTS

LOADING MACHINE

Application filed December 19, 1930. Serial No. 503,503.

This invention relates to loading machines and more particularly to improvements in the material gathering means of machines for loading coal or similar loose material in mines.

An object of this invention is to provide an improved coal loading machine. Another object is to provide an improved material gathering mechanism for such machines whereby the material to be loaded is gathered and moved onto the conveying means of the machine in an improved and more effective manner. A further object is to provide improved material gathering means of the character wherein the material is gathered and moved onto the conveying means by a shoveling action. A further object is to provide improved gathering means of the aforesaid character wherein a shovel blade is employed and having associated therewith improved means for imparting to the shovel blade a shoveling motion. Still another object is to provide an improved gathering mechanism for a coal loading machine whereby the loose coal is gathered and moved onto the conveying means in an improved manner and whereby the standing coal at the face may be undermined and broken down onto the shovel and moved onto the conveying means of the machine. These and other objects of the invention will, however, hereinafter more fully appear.

In the accompanying drawings there is shown for purposes of illustration one form which the invention may assume in practice. In these drawings,—

Fig. 1 is a plan view of the forward portion of a coal loading machine having embodied therein the illustrative form of the improved gathering means;

Fig. 2 is a side elevational view of the machine shown in Fig. 1, parts being broken away to illustrate details of construction;

Fig. 3 is a transverse vertical sectional view taken substantially on line 3—3 of Fig. 2;

Fig. 4 is a detail sectional view taken on line 4—4 of Fig. 1;

Fig. 5 is a transverse vertical sectional view taken substantially on line 5—5 of Fig. 2;

Fig. 6 is an enlarged fragmentary side elevational view of the gathering mechanism shown in Fig. 2 with parts shown in vertical section to illustrate structural details; and

Fig. 7 is a detail sectional view taken on line 7—7 of Fig. 6.

In this illustrative construction the improved gathering mechanism is shown embodied in a loading machine of the track supported and guided type but since the particular type of loading machine with which the improved material gathering mechanism is associated is not of primary importance and as the improved gathering mechanism may be incorporated in loading machines of various types, details of the machine as an entirety are not disclosed herein. The machine disclosed herein generally consists of a wheeled truck 1 having truck wheels 2 adapted to run along a mine track 3. Mounted on the truck is a frame 4 confined to horizontal swinging movement relative to the truck as is usual in machines of the type disclosed and having pivotally mounted thereon at 5 for vertical swinging movement a frame 6 terminating at its forward end in a shovel 7. Guided on the frame 4 and the shovel frame 6 is an endless flight elevating conveyor 8 with which the improved material gathering mechanism generally designated 9 cooperates in the loading of the material acted upon thereby.

In the present construction, carried by the frame 4 is a motor 10 having fixed to its power shaft a spur pinion 11 meshing with and driving a large spur gear 12 (see Fig. 2) fixed to a transverse shaft 13 suitably journaled within the frame 4. The shaft 13 drives through a train of spur gears 14, 15 and 16, a horizontal shaft 17, herein arranged parallel with and above the shaft 13 and likewise suitably journaled within the frame 4. Fixed to this shaft are sprockets 18, 18 which engage and drive the side chains 19, 19 of the conveyor 8. It will thus be seen that during running of the motor 10 the gathering conveyor 8 is rapid-

ly circulated within its guides. As previously mentioned, the detail construction of the machine as a whole is not of primary importance and therefore further description thereof is thought unnecessary.

Now referring to the improved gathering mechanism 9, it will be noted that extending longitudinally of the machine at opposite sides of the shovel frame 6 are parallel arms 20, 20 having journaled thereon about a transverse axis at 21 at their forward ends a shovel blade 22. As illustrated, this shovel blade is of double convex cross section, as shown in Fig. 6, and is formed by curved surfaces 23 converging at their ends along transverse lines lying in a transverse plane passing through the axis of rotation of the blade to form transverse penetrating edges 24 and 25. As shown in Fig. 7, formed at the ends of the double convex portion of the shovel blade 22 are stub shafts 26 journaled in bearings 27 carried within the supporting arms 20, 20. The shovel 7 is provided with an inclined plane surface 28 extending completely across the shovel frame, and the shovel blade, during operation thereof, rests upon and slides over this plane surface as will be hereinafter described. In this illustrative construction the parallel arms 20, 20 are pivotally connected at 29 on bearing sleeves supported by stub shafts or crank pins 30 formed on a pair of cranks 31, 31. As shown most clearly in Fig. 5, the inner ends of these cranks are keyed at the ends of a horizontal shaft 32 extending transversely of, and suitably journaled within the frame 4.

Various devices may be employed for effecting swinging of the cranks to thereby effect swinging of the arms 20, 20 and herein is shown a pair of chain sprockets 33, 33 fixed at the opposite ends of the shaft 13 (see Fig. 3) and these sprockets are connected by endless transmission chains 34 to a pair of sprockets 35, 35 keyed at the opposite ends of a horizontal shaft 36. In the present instance, this shaft is arranged parallel with and above the shaft 32 and likewise suitably journaled within the frame 4 and extends transversely between the top and bottom flights of the gathering conveyor 8, as clearly shown in Fig. 5. The sprockets 35 drive the shaft 36, and fixed at the ends of this shaft is a pair of spur gears 37, 37 meshing with spur gears 38, 38 keyed at the ends of the transverse shaft 32 to which the cranks 31 are also fixed. It will thus be seen that as the conveyor 8 is rapidly circulated within its guides, the cranks 31 are simultaneously turned about their axes through the chain and sprocket connections 33, 34, 35 and the trains of spur gears 37, 38. Herein keyed to the crank pins 30 are chain sprockets 39, 39 which drive through endless transmission chains 40, 40

70 housed in the arms 20, 20, sprockets 41 fixed, as shown in Fig. 4, to a shaft 42, journaled within each of the arms. Also fixed to each of these shafts 42 is a chain sprocket 43, which drives through an endless transmission chain 44, also housed within the arm, a sprocket 45, these sprockets being fixed to the stub shafts 26, 26 formed integral with the shovel blade 22. It will thus be seen that as the cranks 31, 31 turn about their axes, an oscillatory swinging motion is imparted to the arms 20, 20 thereby causing the shovel blade 22 to be reciprocated back and forth over the plane surface 28 of the shovel while at the same time the shovel blade will be given a rotative motion through the sprockets 39, chains 40, sprockets 41, 43, chains 44 and sprockets 45 fixed to the opposite ends of the shovel blade, the shovel blade being rotated one-half a revolution up- 80 on each complete revolution of the cranks 31. 85

From the foregoing it will be seen that as the shovel blade is rotated about its own axis it is at the same time given a linear motion back and forth relative to the shovel 90 by the swinging arms 20, 20. When the arms are in the full line position shown in Fig. 6, they are moved forwardly by the cranks which turn in a clockwise direction as viewed in Fig. 6, but relatively slowly due to the angular position of the cranks 95 at that time. There is therefore comparatively great penetrating power. In this position, as indicated at A in Fig. 6, the forward penetrating edge of the shovel blade 100 has already entered beneath the material to be loaded and has started to lift up at its forward edge. The forward edge of the shovel blade moves upwardly until it assumes the position indicated at B in Fig. 105 6. The linear motion of the blade will then be relatively fast while it moves from position B to position C and the shovel blade will, during this last movement, be located in its rearmost position adjacent the forward 110 end of the elevating conveyor 8 thereby permitting the material to be discharged from the shovel blade onto the conveyor. As the shovel blade moves from position C to position D, the angular movement of the shovel 115 blade will again be relatively fast and the linear motion will change direction so that the shovel blade will then move forwardly along the shovel. While the shovel blade moves forwardly from position C to position A, the lower and forward penetrating edge of the blade scrapes over the plane surface 28 of the shovel and the blade is in such position where it will meet the least resistance when the shovel blade is forced 120 under the pile of material. It will thus be seen that a shoveling motion is transmitted to the shovel blade so that the blade is moved forwardly beneath the material, then 125 lifted upwardly, moved rearwardly like a 130

hoe along the shovel and forces the lifted material onto the conveyor, the shovel blade thereafter returning to a position wherein it again moves beneath the material.

5 In the use of the improved material gathering means, the machine is propelled bodily along the trackway, the shovel frame 6 being in its downward position as shown in Fig. 2 at that time, to force the shovel 7 into the pile of material. Simultaneously the shovel blade 22 is actuated to dig beneath the material, lift the material upwardly and rearwardly onto the shovel and thereafter to discharge the material onto the elevating conveyor 8. When standing coal is encountered, that is coal which has been shot down but not sufficiently shattered to permit easy gathering thereof, the gathering mechanism is operated to undermine the standing coal, 20 the shovel blade 22 digging beneath the standing coal thereby breaking the coal down onto the shovel from which it is moved by the shovel blade onto the elevating conveyor. It will be noted that the 25 shovel blade may be operated to break down coal at different elevations from the mine floor simply by adjusting the position of the vertically swingable shovel frame. These and other uses and advantages of the improved loading machine will be clearly apparent to those skilled in this art.

While there is in this application specifically described one form which this invention may assume in practice, it will be understood that this form of the same is shown for purposes of illustration and that the invention may be modified and embodied in various other forms without departing from its spirit or the scope of the appended 40 claims.

What I claim as new and desire to secure by Letters Patent is:

1. In a loading machine, the combination with a shovel and conveying means extending toward the forward edge of said shovel, of material gathering means comprising a rotatable material gathering element guided on said shovel, and mechanism for rotating and simultaneously bodily moving said gathering element relative to said shovel to gather and move the material to be loaded onto the conveying means.

2. In a loading machine, the combination with a shovel and conveying means extending toward the forward edge of said shovel, of material gathering means comprising a material gathering element rotatable about a horizontal axis and guided on said shovel, and mechanism for rotating and simultaneously bodily moving said gathering element relative to said shovel to gather and move the material to be loaded onto the conveying means.

3. In a loading machine, the combination with conveying means, of material gather-

ing means comprising a shovel blade rotatable about a horizontal axis and having oppositely disposed material penetrating edges between which the axis aforesaid lies, and mechanism for rotating and simultaneously reciprocating said blade back and forth longitudinally of said conveying means to gather and move the material to be loaded onto the conveying means. 70

4. In a loading machine, the combination with conveying means, of material gathering means comprising a shovel angularly movable about a horizontal axis and having oppositely disposed material penetrating edges between which the axis aforesaid lies, and mechanism for angularly moving and simultaneously bodily reciprocating said shovel back and forth to gather and move the material to be loaded onto the conveying means. 75

5. In a loading machine, the combination with a shovel and conveying means extending toward the forward edge thereof, of material gathering means comprising an angularly movable shoveling element guided on said shovel, and mechanism for simultaneously angularly moving and bodily reciprocating said shovel element along said shovel to gather and move the material to be loaded onto the conveying means. 80

6. In a loading machine, the combination with conveying means, of material gathering means for moving the material to be loaded onto the conveying means including a single rotatable shovel blade of elliptical shaped cross section having curved surfaces terminating along lines lying in a plane passing through the axis of the shovel blade, and mechanism for bodily moving and rotating said blade to impart thereto a shoveling motion. 85

7. In a loading machine, the combination with conveying means, of material gathering means for moving the material to be loaded onto the conveying means including an angularly movable shovel of elliptical shaped cross section having oppositely curved surfaces terminating along lines lying in a plane passing through the axis of the shovel, and mechanism for angularly and simultaneously bodily moving said shovel to impart thereto a shoveling motion. 90

8. In a loading machine, the combination with a shovel and conveying means extending toward the forward edge thereof, of material gathering means for moving the material to be loaded onto the conveying means including an angularly movable shovel blade guided on said shovel and of double convex cross section having curved surfaces terminating along lines lying in a plane passing through the axis of angular movement of the shovel blade, and mechanism for simultaneously angularly and bodily moving said 105

shovel blade to impart thereto a shoveling motion.

9. In a loading machine, the combination with conveying means, of material gathering means comprising a shovel blade rotatable about a horizontal axis and having oppositely disposed material penetrating edges, and mechanism for rotating and simultaneously reciprocating said blade back and forth to gather and move the material to be loaded onto the conveying means including mechanism automatically rotating said shovel half a turn during each complete reciprocation thereof.
10. In a loading machine, the combination with conveying means, of material gathering means for moving material to be loaded into the field of action of the conveying means including a pair of arms, means for supporting the rearward ends of said arms with respect to which said arms are freely swingable, means for positively moving said supporting means to effect movement of said arms, a shovel rotatably supported by the forward ends of said arms, and means for unidirectionally rotating said shovel during the movements of said arms.
11. In a loading machine, the combination with conveying means, of material gathering means for moving material to be loaded into the field of action of the conveying means including a pair of arms, means for supporting the rearward ends of said arms with respect to which said arms are freely swingable, means for positively moving said supporting means in circular orbits to effect

movement of said arms, a shovel rotatably supported by the forward ends of said arms, and means for rotating said shovel during the movements of said arms.

12. In a loading machine, the combination with conveying means, of material gathering means for moving material to be loaded into the field of action of the conveying means including a pair of arms, means for supporting the rearward ends of said arms with respect to which said arms are freely swingable, means for positively moving said supporting means to effect movement of said arms, a shovel rotatably supported by the forward ends of said arms, and means deriving its motion from the motion of the means for positively moving the arms supporting means for rotating said shovel unidirectionally during the movements of said arms.

13. In a loading machine, the combination with conveying means, of material gathering means for moving material to be loaded into the field of action of the conveying means including a pair of arms, means for supporting the rearward ends of said arms with respect to which said arms are freely swingable, means for positively moving said supporting means in circular orbits to effect movement of said arms, a shovel rotatably supported by the forward ends of said arms, and means including a toothed transmission member rotatable bodily about the axis of said orbits for rotating said shovel during the movements of said arms.
